(57) **CLAIM**

The ornamental design for seal member for use in semiconductor production apparatus, as shown and described.

DESCRIPTION

1.-4. Seal members for use in semiconductor production apparatus

4.9 : Partial enlargement of cross-sectional
4.10 : Reference

The present articles are seal members for semiconductor production apparatuses such as chemical vapor deposition apparatuses and dry etching apparatuses; as illustrated in the reproductions **1.10**, **2.10**, **3.10** and **4.10**, each article is to be inserted into grooves of a semiconductor production apparatus; the semiconductor production apparatuses themselves form no part of the claimed designs; the reproductions **1.8**, **2.8**, **3.8** and **4.8** show transverse cross-sectional front views taken along the horizontal centers of the reproductions **1.6**, **2.6**, **3.6** and **4.6**, respectively; the reproductions **1.9**, **2.9**, **3.9** and **4.9** are enlarged views showing left end portions of the cross-sectional views **1.8**, **2.8**, **3.8** and **4.8**, respectively.
